United States Patent Office

Des. 191,605
Patented Oct. 24, 1961

191,605

HOOD OR THE LIKE

Nina L. Andrews, 162 John St., East Providence, R.I.,
and Harold W. Demopoulos, 190 Nelson St., Providence, R.I.

Filed Feb. 23, 1960, Ser. No. 59,483

Term of patent 3½ years

(Cl. D3—13)

FIG. 1

We claim:

The ornamental design for a hood or the like, substantially as shown.
